UNITED STATES PATENT OFFICE.

JOHN SIMON, OF OAKLAND, CALIFORNIA.

DOOR-ALARM.

SPECIFICATION forming part of Letters Patent No. 231,502, dated August 24, 1880.

Application filed June 26, 1880. (No model.)

To all whom it may concern:

Be it known that I, JOHN SIMON, of the city of Oakland, in the county of Alameda and State of California, have invented an Improved 5 Door-Alarm; and I do hereby declare that the following is a full, clear, and exact description thereof, reference being had to the accompanying drawings.

My invention relates to that class of door-10 alarms in which a gong is attached to the lock-spindle inside of the house, instead of the ordinary inside door-knob, so that the turning of the lock-spindle to withdraw the bolt and open the door strikes the gong and sounds an 15 alarm.

The object of my invention is, first, to simplify the striking mechanism of the gong; and, secondly, to provide an improved arrangement for disconnecting the cam and striker when it 20 is desired to prevent the turning of the spindle from striking no alarm.

Referring to the accompanying drawings, Figure 1 is a view of my invention applied to a mortise-lock, a part of the shell of the 25 alarm being broken away. Fig. 2 shows a front view, in detail, of the alarm mechanism in working position. Fig. 3 is a similar view, showing the parts of the apparatus thrown out of action. Fig. 4 is a longitudinal section of the 30 parts in detail. Fig. 5 shows details of the pawl and dog.

Let A represent a section of a door, in or to which a door-lock is secured. B is the spindle or shank which passes through the door-lock, and serves, when turned, to throw back 35 the latch and allow the door to open.

C is the ordinary door-knob, which is secured to the end of the shank on the outside of the door, while the gong-knob is secured on its opposite end, inside the house, so as to serve as 40 the inside knob.

The shank or spindle B extends entirely through the gong-knob on the inside of the door, and has a thread cut on its end, on which 45 the gong D is screwed.

Between the gong and door I place upon the shank or spindle a sleeve, E, which has a circular flange, f, fitting against the door, and upon this sleeve I place a concave disk, G, 50 facing outward, so that the concave disk forms

the inner half of the knob, while the gong forms the outer half.

On the end of the sleeve E, inside the concave disk G, I secure a plate, h. This plate therefore turns with the sleeve and its flange, 55 independent of the knob-spindle. To this plate I secure the striker j and its arm k, which are connected together at right angles in the usual way.

A screw, i, passes through the end of the 60 arm k at the angle, while the opposite end of the arm is bent inward, so as to form a toe, O.

A wire spring, S, has one end attached to the toe, while its middle is wound around the projecting screw and its opposite end is fastened to the plate h, so that the spring keeps the striker in place.

A cam or trip lever, l, is secured to the lock-spindle close to the plate, and it has one or more teeth or points, n, formed on its end, so 70 that when the spindle is turned the teeth strike the toe O on the end of the arm k consecutively, and throws the hammer back and causes the gong to strike. This is an extremely simple and effective arrangement of the striker. 75

The flange f has a circular slot, r, cut in it near its edge on opposite sides, and a screw or pin, t, passes through each slot at opposite corners, so that the flange can be turned in either direction as far as the screws or pins 80 will allow, and as the sleeve E and plate h are connected with the flange, they will also be turned with it. When the flange is turned as far as it will go in one direction the plate h is 85 in position to allow the cam or trip lever l to operate the striker, but when it is turned as far as it will move in the opposite direction the plate is turned so as to carry the striker out of reach of the trip-lever, when the spindle can be turned without striking the gong. 90

A small handle, v, is secured to the flange, by means of which the flange can be turned, and a latch, w, is arranged to engage with a notch, x, in the edge of the flange, in order to secure it in position and hold it against the 95 strain of the trip-lever when the device is set for striking. This forms an exceedingly simple arrangement by which the gong can be used or not, as desired.

Having thus described my invention, what 100

I claim, and desire to secure by Letters Patent, is—

1. In a knob-gong, the combination, with the spindle, of the plate *h*, cam or trip lever *l*, located upon the spindle, hammer *j*, having the arm *k* and spring *S*, and the sleeve *E*, having the flange *f* and connected to the plate *h*, the flange *f*, having curved slots *r*, with screws *t* working in opposite corners of said slots, and a slot, *x*, with which engages a holding device, *w*, substantially as and for the purpose set forth.

2. In a door-knob gong, the sleeve *E* and plate *h*, connected with a flange, *f*, said flange having the curved slots *r*, with their pins *t*, and having the latch *w* arranged to engage with a notch, *x*, in its edge, substantially as above specified.

In witness whereof I have hereunto set my hand and seal.

JOHN SIMON. [L. S.]
